UNITED STATES PATENT OFFICE.

CASPAR BUBERL, OF NEW YORK, ASSIGNOR TO HIMSELF AND OSCAR NEUBERT, OF NEWTOWN, N. Y.

DESIGN FOR A STATUETTE.

SPECIFICATION forming part of Design No. 12,522, dated October 11, 1881.

Application filed August 18, 1881. Term of patent 14 years.

To all whom it may concern:

Be it known that I, CASPER BUBERL, a citizen of the United States, residing at New York, in the county and State of New York, have 5 originated and Designed a Statuette, of which the following is a full, clear, and exact description, reference being had to the accompanying photographic illustration, making part of this specification.

- 10 My design is a statuette adapted to flower-holders, chandeliers, and other articles for purposes of use or ornament, and is illustrated in the accompanying photograph, which represents a front view.
- 15 My design consists of the figure of a boy standing in an erect position upon a pedestal with the feet separated and clothed in a dress-coat. The right hand of the figure is partially raised and grasps a crayon-holder, while the 20 other hand is extended and grasps a bouquet of flowers. Suspended at the left side of the figure of the boy is represented a portfolio supported by a strap slung across the right shoulder. The head of the boy is poised as though looking at the bouquet of flowers, and in a direction opposite to the crayon-holder, which he holds in his right hand. 25

I do not broadly claim the representation of a boy clothed in a dress-coat and one hand sustaining a crayon-holder, a strap being slung 30 across one shoulder and supporting a portfolio, and the other hand supporting the head.

What I claim as new, and desire to secure by Letters Patent, is—

The design of a statuette, consisting of the 35 figure of a boy clothed in a dress-coat and a hat, sustaining by one hand a crayon-holder and by the other a bouquet of flowers, and having slung diagonally across one shoulder a strap supporting a portfolio, as shown and described. 40

In testimony whereof I have hereunto set my hand and seal in the presence of two subscribing witnesses.
